UNITED STATES PATENT OFFICE.

JULIUS ERDOES, OF NEW YORK, N. Y., ASSIGNOR TO JOSEPH DIXON CRUCIBLE COMPANY, OF JERSEY CITY, NEW JERSEY, A CORPORATION OF NEW JERSEY.

DISPLAY CASE.

Application filed December 21, 1923. Serial No. 681,912.

The invention relates to an improvement in display cases adapted to contain and display packages of goods for sale, cases of this character being provided with space for printed or pictorial matter advertising or describing the goods.

The object of the present invention is to produce an improved display case of this character having provision for more attractively presenting or displaying the goods for sale and at the same time affording added space for advertising, descriptive, pictorial or other matter designed to attract and hold the attention of the purchaser and afford him more or less complete information as to the goods displayed. Although the display case of the present invention is adapted for containing and displaying various kinds of goods, the invention is more particularly concerned with providing an improved display case for containing and displaying cylindrical packages or boxes of leads for mechanical, self-pointing, or automatic pencils. Such leads usually vary in their degree of hardness or softness, the degree of hardness or softness of the leads depending upon the character of the work to which they are to be put. One of the features of the present invention is to provide a separate compartment for the boxes containing leads of the same degree of hardness or softness. Each compartment will be appropriately labeled and only boxes containing leads of a particular hardness or softness will be placed in that compartment. This arrangement conduces to convenience and a saving of time for both the salesman and the purchaser. The invention also embraces various improvements and arrangements of parts as described hereinafter and particularly pointed out in the appended claims.

In the accompanying drawings illustrating the preferred form of the invention Fig. 1 is a front elevation of the improved display case; Fig. 2 is a rear elevation of the display case; Fig. 3 is a vertical section taken through one of the compartments, showing the manner in which the packages are contained therein; Fig. 4 is a section

taken along the line 4—4 of Fig. 2; and Fig. 5 is a section taken along the line 5—5 of Fig. 2.

The improved display case, as shown in the drawings, comprises a display surface 55 or front 6 preferably composed of metal, such as tinned iron treated with japan or other finishing varnish. The lateral and bottom edges 7 of the plate from which the display surface 6 is formed are turned over 60 rearwardly to stiffen the display surface and incidentally to lend a more pleasing appearance to these parts. The compartments 8 for holding or containing the packages, such as the cylindrical boxes of leads, are 65 supported from the rear side of the front plate 6. These compartments are vertically arranged and are long enough to hold 5 or 6 or more boxes of leads. There may be any desired number of compartments. In 70 the illustrated form of the invention there are eight compartments each adapted to hold boxes containing leads of a different degree from the very softest used up to the very hardest.

The compartments 8 may be separately made and attached to the plate 6. Preferably, however, the package containing compartments are formed as evenly spaced corrugations in a single plate or sheet of metal 80 11, so that when the rear plate 11 is secured to the rear side of the front plate it will form therewith a series of evenly spaced, parallel, vertically arranged compartments open at their upper and lower ends. The 85 lateral edges 9 of the rear plate 11 project beyond the compartments to provide means for securing the compartments to the rear side of the plate 6, as by means of the rivets 10. Additional holding means is provided 90 at the top of the compartments in the form of a band 12; this band also affording means for designating the kind of leads to be placed in each compartment. The boxes of leads are conveniently placed in the compartments by way of the open tops, as shown in Fig. 3.

The lower part of each compartment opens into an elongated slot 14 formed in the lower end of the front plate 6 so as to 100

display the lowermost package or box in each compartment and present it for ready and easy removal by the salesman. The openings or slots 14 are about two-thirds or 5 three-fourths of the length of the packages or boxes, as shown in Fig. 3. As each lowermost box passes through the opening 14 it falls onto and is held by a shelf or ledge 15 struck up from the plate 6. The 10 front edge of each shelf is bent upwardly to provide a hook 16 to prevent the accidental displacement of the boxes as they fall into display position on the shelves 15. The packages or boxes are deflected into the 15 openings 14 by means of tongues 18 formed on a strip 19 and projecting upwardly at a rearward angle into the lower ends of the compartments 8, as clearly shown in Fig. 3. The strip 19 is provided with the ears 20 by 20 which the upper edge of the strip is held against the plate 6, the lower edge of the strip fitting under the bottom upturned edge 7 of the plate 6. Each tongue 18 is of such size that it substantially fills the lower end 25 of its compartment, as indicated in dotted lines in Fig. 2. In order that the packages or boxes may slide down easily into the openings 14 when they strike the deflecting tongues 18, the adjacent parts 21 of the 30 plate 6 over the upper ends of the slots are bellied out, as shown in Figs. 1 and 4.

The improved display case, constructed as described above, may be hung up on the wall of the store by means of the hole 22 35 in the strip 12; or it may be set up for display on the counter by means of the easel 24 which is secured to the case by the ears 25 struck up from the flanges 9. Over each opening 14 may be placed appropriate marks 40 descriptive of the kind of lead contained in the boxes in the corresponding compartment. This descriptive matter is not only of convenience to the storekeeper or salesman but also informs the purchaser just what degree 45 of hardness or softness the leads have and how these different degrees of hardness and softness are distinguished one from the other so as to enable him to secure the kind of lead best adapted for the particular purpose in hand. On the strip 12 and opposite the top 50 of each compartment may also be placed the appropriate description corresponding to the description over each opening 14 to enable the storekeeper or salesman to place in each 55 compartment the boxes of lead for which it is intended, the boxes, of course, being furnished with corresponding descriptive matter. When a box of leads is sold and removed the next box falls by gravity down 60 through the opening 14 and comes to rest on the shelf 15. The relatively large and clear space above the openings 14 and raised 65 portions 21 may be occupied by any kind of pictorial, advertising or descriptive matter best adapted to attract the attention of the

purchaser and inform him concerning the nature of the goods displayed for sale.

Having thus described the invention what I claim as new is:—

1. A display case for cylindrical packages 10 comprising, a front plate, a series of vertically disposed tubular compartments arranged on the rear side of the plate and having open tops for the reception of the packages, the front plate being provided in its lower portion with slots opposite the lower ends of the compartments, and having portions of the plate above the slots swelled outwardly, a deflector located in the lower end of each compartment to deflect the articles 75 out through the slot and a shelf below each slot to hold the lowermost article in position to be removed.

2. A display case for cylindrical packages 85 comprising, a front plate, a rear plate having a series of evenly spaced parallel corrugations of uniform depth secured to the rear side of the front plate so as to form therewith a series of vertically arranged tubular compartments, said front plate being 90 provided in its lower end with a series of openings opposite the lower ends of the compartments, means comprising tongues extending from the front plate of the case upwardly into and obliquely across the compartments adjacent their discharge ends for deflecting the packages contained in the compartments out through the openings, and means for holding the lowermost package 95 in each compartment in position to be removed.

3. A display case comprising, a front plate having a series of openings in the lower end thereof, a portion of the front plate below each opening being deflected to form a shelf 105 to support a package in position to be removed, a series of vertically disposed compartments arranged on the rear side of the plate and having their lower ends in register with the openings and a series of deflectors for deflecting the articles from the compartments out through the openings.

4. A display case comprising, a front plate having a series of elongated slots in its lower end, the material of the plate being struck 115 up at the bottom end of each slot to provide a shelf to support an article in position to be removed, a series of vertically arranged compartments on the rear side of the plate having their lower ends in register with the 120 openings in the front plate, and a strip of material secured to the lower rear side of the plate and having upwardly projecting tongues projecting within the lower ends of the compartments to deflect the packages in 125 the compartments out through the openings.

5. A display case for cylindrical packages comprising, a front plate having a series of slots in its lower end, a shelf below each slot to support a package in position to be re- 130

moved, a rear plate having a series of corrugations formed therein so that when the rear plate is secured to the rear side of the front plate it forms therewith a series of tubular, vertically arranged compartments having their lower ends in register with the slots in the front plate, a series of tongues

projecting from substantially the bottom of the slots upwardly and rearwardly into the lower ends of the compartments to act as deflectors to deflect the articles in the compartments out through the slots and onto the shelves.

JULIUS ERDOES.
